Primary Examiner — Barbara Fox*Assistant Examiner* — Dana K Weiland(74) *Attorney, Agent, or Firm* — Oppedahl Patent Law Firm LLC(57) **CLAIM**

The ornamental design for an electronic device, as shown and described.

DESCRIPTION

FIG. 1 is a left side view of an electronic device showing the new design;

FIG. 2 is a right side view thereof;

FIG. 3 is an enlarged view of the portion of the electronic device circled in FIG. 2;

FIG. 4 is a perspective view of the electronic device shown in FIG. 1;

FIG. 5 is another perspective view thereof in an alternate configuration; and,

FIG. 6 is another perspective view thereof in an alternate configuration.

The broken lines shown in the drawings illustrate portions of the electronic device that form no part of the claimed design.

1 Claim, 5 Drawing Sheets(56)
